E. L. GLAUM.
INFANT'S COLLAPSIBLE BED.
APPLICATION FILED AUG. 2, 1919.

Patented Apr. 11, 1922.

Inventor:
Ellen L. Glaum,
by: Howard Fischer
Attorney.

UNITED STATES PATENT OFFICE.

ELLEN L. GLAUM, OF DETROIT, MINNESOTA.

INFANT'S COLLAPSIBLE BED.

1,412,177.

Specification of Letters Patent. Patented Apr. 11, 1922.

Application filed August 2, 1919. Serial No. 314,945.

To all whom it may concern:

Be it known that I, ELLEN L. GLAUM, a citizen of the United States, residing at Detroit, in the county of Becker and State of Minnesota, have invented a new and useful Improvement in Infants' Collapsible Beds, of which the following is a specification.

My invention relates to an infant's collapsible bed, the primary object of which is to provide a bed which is easily collapsed so that it can be folded into a compact state, while on the other hand when set up for use it is adapted to form a durable bed or crib for an infant.

The invention further provides a collapsible bed with flexible enclosing side walls and bottom portion which is detachably held to supporting rods to the legs of the bed, the flexible portions extending across each other to form a strong, durable bottom portion for the bed. The flexible sides and bottom portion of the bed can be formed of any suitable material, such as textile, leather, rubber cloth, or any other suitable material to provide flexible sides and bottom portions, a feature which is desirable, particularly for an infant's bed or crib.

It is also an object of my invention to provide suitable locking means to detachably hold the spacing and supporting rods to the legs of the bed so that the bed can be quickly set up or taken down. In this manner an inexpensive infant's or other bed is provided, which can be made sufficiently strong and durable, and yet light in weight and collapsible into a very compact state.

In the drawings, which form part of this specification:

Figure 1 illustrates a perspective view of my bed, as it would appear when set up for use.

Figure 2 is a side elevation of the bed.

Figure 3 is a diagrammatic cross section on the line 3—3 of Figure 2.

Figure 4 is a diagrammatic longitudinal cross section of the bed.

Figures 5, 6, 7 and 8 are perspective views of detail portions of the bed.

Figure 9 is a perspective view of a detail portion of an alternative construction of the bed.

In the drawing, the bed A is provided with supporting legs 2, which are formed of wood or any other suitable material and are adapted to be spaced apart by parallel extending pairs of side spacing rods 3, while pairs of

parallelly extending end spacing rods 4 form the end spacers for the bed A.

The side spacing rods 3, which are naturally longer than the other spacing rods, are formed in two parts 5 and 6, so that they can be taken apart easily to allow folding in a compact state. The portion 5 is formed with an engaging lug 7, which is adapted to engage in the bayonet slot 8, formed in the inner end of the hollow member 6 so that the members 5 and 6 can be rigidly keyed together when desired for use. The outer ends of the members 5 and 6 are formed with eye portions 9 and 10, respectively.

The end rods 4, which are shorter than the rods 3, are formed in a single piece and have eyes 11 formed on their ends similar to the eyes 9 and 10.

The legs 2 are formed with a longitudinally extending recess 12 and upper and lower notch recesses 13 and 14, into which the eyes 9 and 10 of the rods 3 and the eyes 11 of the rods 4 are adapted to extend so as to communicate with the recess 12, and a suitable key rod 15 is provided which is adapted to extend into the recess 12 and to engage the eyes 9 and 10 of the rods 3 and the eyes 11 of the rods 4 when the spacing rods 3 and 4 are positioned between the legs 2 so as to rigidly key the rods 3 and 4 to the legs 2.

A suitable engaging head 16 is formed on the key rods 15, which projects from the upper portion of the legs 2 and also gives an ornamental appearance to the bed or crib A when the same is set up. The eyes 9 and 10 of the rods 3 and the eyes 11 of the rods 4 are adapted to be so positioned in the recesses 13 and 14 of the legs 2 that the key rod 15, when inserted in the recess 12 will engage the eyes to hold the ends of the rods locked rigidly to the legs of the bed, the rods 4 being positioned above the rods 3 with the eyes of the rods coinciding.

A flexible strip B has its ends hemmed by suitable stitching 17 so as to form an engaging loop 18 on either end thereof, through which the upper end rods 4 are passed to hold the flexible strip in position on the bed A. The flexible strip B extends downward to form flexible end wall portions 19, the strip B extending around the lower end rods 4 with its intermediate portion 20 extending horizontally to form a bottom portion for the bed A. The strip B is stretched sufficiently taut from the loops 18 to give a

neat appearance for the bed A. A second flexible strip C has its ends hemmed by suitable stitching 21 to form holding loops 22, which are adapted to be engaged by the 5 upper rods 3 and the strip C extends downward to form flexible side walls 23 and a bottom portion 24, which extends across and below the lower side rods 3, the strip C being held taut in a similar manner as the 10 strip B, while each of the strips B and C are of the width and length of the bed, respectively. Thus the portions 20 and 24 of the strips B and C extend across and form the bottom for the bed A to provide a durable construction for the bed.

It is obvious that the flexible members B and C can be formed of any suitable textile material or any other suitable material which is desired to be used for the bed A. 20 The construction of the bed A provides a simple, inexpensive device, which can be quickly set up or collapsed and thus provide a bed which is very desirable, particularly for infants, it being understood, however, 25 that the bed can be made strong and durable in larger sizes. This construction of bed, when collapsed, can be folded into a very compact state, the flexible members B and C being folded or wrapped about the supporting legs and spacing rods so that if it is desired the bed A, when made of a size for an infant, can be easily carried in a suitcase.

The details illustrated in Figure 9 show an alternative way of connecting the jointed 35 rods 3. In this construction the rod is formed with hollow end portions 25, only a portion of which is illustrated in the drawing. The end portions 25 have their inner ends formed with bayonet slots 26, which engage the lugs 27 on the key member 28 to lock the ends 25 of the rod together. The outer portions of the rods 25 are adapted to be formed with suitable eyes, such as 9 and 10, of ordinary construction and not 40 illustrated. It is also obvious that the rods 3 can be jointed in any suitable way, but as they are longer than the other spacing rods, it is desirable to have them separable or formed in two parts so as to allow the folding 45 of the bed into a more compact state.

It is a material advantage in having an infant's bed made of the construction illustrated, providing flexible side enclosing walls and bottom portion, which can be easily removed and laundered if it is desired and 55 when the bed is set up it is of a neat tidy construction with the members B and C drawn taut over the rods 3 and 4.

In touring or travelling, an infant's bed 60 of this construction is very desirable.

In accordance with the patent statutes I have described the principles of operation of my invention, together with the apparatus which I now consider to represent the best 65 embodiment thereof, but I desire to have it

understood that the construction shown is only illustrative and that the invention can be carried out by other means and applied to uses other than those above set forth within the scope of the following claims.

I claim—

1. A collapsible bed comprising a frame having upright corner supporting legs, upper and lower longitudinally parallel brace rods for the sides and ends detachably held by said supporting legs, a flexible strip of the same width as the bed, having its ends secured to the upper end brace rods and having its intermediate portion passing below the lower end brace rods, and a second and 80 separate flexible strip equal in width to the length of the bed having its ends secured to the upper side brace rods and extending down the side with its intermediate portion extending below and across the lower side 85 brace rods.

2. A collapsible bed comprising a frame having upright corner supporting legs, upper and lower longitudinally parallel brace rods for the sides and ends detachably held by said supporting legs, notches formed in said legs for receiving the ends of said brace rods, locking keys extending longitudinally in said supporting legs and engaging eyes formed in the ends of said brace rods for 95 detachably holding said brace rods to said supporting legs, a textile strip having its ends secured to the upper end brace rods with its intermediate portion passing below the lower end brace rods and a second and 100 separate textile strip having its ends secured to the upper side brace rods with its intermediate portion extending below and across the lower side brace rods.

3. A collapsible bed having the parts 105 thereof adapted to be arranged in parallel order and formed in a roll of a length equal to some of the shorter elements thereof comprising upright corner supporting legs, upper and lower pairs of parallel rails demountably attached to said legs and of a length less than the height of said legs, collapsible parallel longitudinal rails detachably secured to said legs, said longitudinal rails being adapted to be taken apart at a 110 point such that the length of the longer portions of said rails are substantially equal to the length of said legs, a flexible fabric strip of a width equal to said end rails 115 adapted to be secured to said upper end rails and passing below and under said lower end rails to partially form a bottom for a bed and a similar and separate strip equal to the width of the length of the bed having its ends secured to the upper side rail and extending down the sides and below said bed to form an additional bottom support across the same.

ELLEN L. GLAUM.
